UNITED STATES PATENT OFFICE.

ROBERT H. BURNS AND HENRY M. MASON, OF KENNEWICK, WASHINGTON.

MILK-COOLER.

1,148,351.

Specification of Letters Patent. Patented July 27, 1915.

Application filed May 31, 1913. Serial No. 771,017.

To all whom it may concern:

Be it known that we, ROBERT H. BURNS and HENRY M. MASON, citizens of the United States, residing at Kennewick, in the county 5 of Benton and State of Washington, have invented new and useful Improvements in Milk-Coolers, of which the following is a specification.

The present invention has reference to 10 liquid coolers, and more particularly to devices for cooling milk, cream, and buttermilk. It resides, briefly, in the production of an extremely simple and inexpensive device for cooling liquids of the aforementioned class which is so constructed as to 15 effect the cooling of the liquid by means of a revolving ice-container disposed within the main liquid receptacle and carrying a fan or blade that serves to agitate the liquid 20 during the time that the receptacle is in motion, thereby equalizing the liquid.

An embodiment of the invention is illustrated in the accompanying drawing, whereof:

25 Figures 1 and 2 are, respectively, a side elevation and a longitudinal section of the improved cooler; Fig. 3 is a plan view of the cooler, part of the ice-container cover being broken away; Fig. 4 is a detail sectional view, on an enlarged scale, of the liquid-discharge device; and Fig. 5 is an enlarged fragmental perspective view of the upper portion of the ice-container.

As shown in said drawing, the cooler 35 preferably comprises the following main parts, to wit: outer and inner receptacles adapted to contain, respectively, the liquid to be cooled and the ice, a stand or base whereon the outer receptacle rests, a cover 40 for the said outer receptacle, and a device for rotating the inner receptacle.

Both receptacles, which are indicated by the reference numerals 1 and 2, are constructed, by preference, of glass, and are 45 in the form of vertical cylinders closed at their lower and open at their upper ends. The outer receptacle 1 rests, as originally stated, upon the base, which latter consists of a galvanized iron inner ring 3 and an 50 outer nickel ring 4 arranged concentrically and having their upper edges hooked or bent to provide a supporting seat 5 and a coacting retaining lip 6 for the circumferential rib 7 formed upon the bottom edge 55 of the said outer receptacle.

The inner or ice-containing receptacle 2

is arranged concentrically within the outer receptacle and is of appreciably less diameter than the latter, so as to produce the interposed annular chamber 8 that receives the 60 milk or other liquid to be cooled. The bottom wall of this receptacle is formed with a central bearing opening 9 to receive the pivot 10 formed upon a centrally-located boss 11 with which the bottom wall of the 65 outer receptacle is provided, and its main or vertical wall has formed thereon a spiral blade or flange 12, also of glass, that extends from one end of the receptacle to the other and is of a width which very closely approaches that of chamber 8. Preferably, a single continuous spiral flange is employed which encircles the inner receptacle 2 to 70 form a suitable number of convolutions about the same, and this flange has such a 75 pitch as to produce essentially a vertical circulation or movement of the liquid rather than a rotary movement thereof, thus insuring uniformity in the character of the liquid from top to bottom of the chamber 80 8 but avoiding any appreciable churning action thereon.

To close the open upper end of the outer receptacle 1, there is provided a cover 13 of any approved design, but preferably constructed of glass. This cover is formed upon its lower face with a circular seat 14 which receives therein the upper edge of the outer receptacle, and said edge is notched at intervals, as indicated by the numeral 15, 90 to receive depending pins or lugs 16 provided in the aforesaid seat, the cooperating parts 15 and 16 constituting a lock that serves to prevent rotation of the cover. The said cover is also provided with a central 95 opening 17, through which the upper end of the inner receptacle projects, and with a filling opening 18 for the milk, the latter opening extending through the cover and being furnished with a removable cap or 100 closure 19.

The device for rotating the inner receptacle 2 preferably comprises a spring motor or clock-work 20 of any suitable type which is rigidly mounted upon a cap-like 105 base member 21 that serves to cover the upper end of said receptacle. The depending flange portion of this cap is provided with inwardly-projecting lugs 22 receivable in notches 23 in the upper edge of the receptacle, so as to insure the rotation of the latter with the cap when the motor is running. 110

In the present instance, the main or working parts of the motor are shown as comprising a series of pinions 24 that are mounted upon the ends of horizontal shafts 5 25 and mesh with the teeth of a sunken annular rack 26 that is formed in the upper surface of cover 13, the said shafts being actuated from the spring or other driving part, (not shown), of the motor.

10 The discharge faucet 27 is located at the bottom of the main or milk-containing receptacle 1 and consists, in the present instance, of a rotary cock or valve 28, fitted in an opening in a spindle-like body portion 29, the L-shaped passage 30 in the valve being brought into and out of registration with the spindle bore 31 when the valve is turned by its handle 32. The aforesaid spindle extends through an opening in 20 the wall of the receptacle, and terminates at its inner end in a head 33; it is held in place by a nut 34 located exteriorly of the said receptacle wall and designed to be tightened thereagainst, a pair of rubber washers 35 25 and 36 being disposed upon opposite sides of said wall and between the same and said nut and spindle head, to provide the requisite liquid-tight joint.

In operation, the motor and its cap are 30 first removed from receptacle 2, and the latter then filled with ice, after which they are replaced, and the receptacle 1 filled with milk or other liquid by way of the opening 18. The motor is then started, to effect the 35 revolution of the ice-containing receptacle, with the result that the milk is rapidly cooled and, at the same time, continuously agitated by means of the spiral flange, whereby the cream is prevented from rising 40 and is distributed evenly throughout the entire body of milk. It is to be understood, however, that the movable receptacle rotates at a very slow rate of speed, so that there 45 is no danger of the flange exercising any churning action whatever upon the milk.

Having fully described our invention, we claim:

1. A cooler of the type specified comprising, in combination, an outer liquid-containing receptacle, an inner refrigerant-containing receptacle surrounded by convolutions of a spiral flange, and means for relatively rotating the inner and outer receptacles to produce vertical circulation of the liquid 50 in the outer receptacle by said flange without appreciable rotary or churning action upon the liquid.

2. A cooler of the type specified, comprising, in combination, an outer liquid-containing receptacle having a relatively fixed cover; a refrigerant-containing receptacle

rotatably mounted within the first-named receptacle and having a surrounding flange with such a pitch as to cause vertical circulation of liquid in the first-named receptacle; and a device mounted upon the top of the second-named receptacle and cooperatively engaged with said cover, for rotating the second-named receptacle to cool the contents of the first-named receptacle and 65 to cause vertical circulation of such contents by said flange.

3. A cooler of the type specified, comprising, in combination, inner and outer glass receptacles adapted to contain, respectively, 70 a refrigerant and the liquid to be cooled; a delivery faucet connected to the outer receptacle; a device for rotating the inner receptacle, to cool the contents of the outer receptacle; and a spiral glass flange surrounding 80 said inner receptacle and having a pitch to agitate the contents of the said outer receptacle in a vertical direction and to avoid churning action when the inner receptacle is rotated.

4. A cooler of the type specified, comprising, in combination, an outer liquid-containing receptacle; a stationary cover therefor provided with a central opening; a refrigerant-containing receptacle rotatably mounted within the first-named receptacle and projecting through said opening; a removable cap locked upon the projecting end of the second-named receptacle; and a device for rotating said second-named receptacle 95 affixed to said cap for removal therewith and cooperatively engaged with said cover.

5. A cooler of the type specified, comprising, in combination, an outer liquid-containing receptacle; a stationary cover therefor 100 provided with a central opening and with an annular rack encircling the same; a refrigerant-containing receptacle rotatably mounted within the first-named receptacle and projecting through said opening; a removable cap locked upon the projecting end of the second-named receptacle; and a spring motor for rotating said second-named receptacle affixed to said cap for removal therewith and including a pinion engaged 105 with said rack.

In testimony whereof we have hereunto set our hands in presence of two subscribing witnesses.
